Fig. 2

Fig. 3

Fig. 4

Fig. 5

Fig. 6

FIG. 1 is a front perspective view of a chain saw embodying our new design.

FIG. 2 is a side perspective view thereof.

FIG. 3 is a top plan view thereof.

FIG. 4 is a side perspective view thereof showing the side opposite that shown in FIG. 2.

FIG. 5 is a front elevational view thereof, and

FIG. 6 is a rear elevational view thereof.

The saw bar is shown fragmentarily in FIGS. 2, 3 and 4 for convenience of illustration.

We claim:

The ornamental design for a chain saw, as shown and described.
